BATHTUB HINGEDLY MOUNTED ON A COLLAPSIBLE STAND

Bernard E. McLaughlin, Tucson, Ariz.

Application September 21, 1949, Serial No. 116,981

10 Claims. (Cl. 4—176)

1

This invention relates to novel and useful improvements in hospital and home equipment.

An object of this invention is to produce a device within the means of an average family for bathing arthritic or other partially incapacitated persons in need of bathing treatment.

Another object of this invention is to render it simple and easy to move a patient from a bed and place the patient in the tub preparatory to receiving a water treatment.

Another object of this invention is to provide such an apparatus whereby it may be easily transported from one place to another and whereby it may be collapsed or folded so as to take up a bare minimum of space.

Another object of this invention is to bathe a partially or totally incapacitated person easily and conveniently and also to transfer that patient or a similarly incapacitated patient to a standing position safely and easily, both of these functions being performed preferably by the same structure.

Ancillary objects and features of novelty will become apparent in following the description of the preferred form of the invention, illustrated in the accompanying drawings, wherein;

Figure 1 is an exploded perspective view of various components of the tub and the patient board;

Figure 2 is a longitudinal sectional view of the device, showing a second position of the tub in phantom;

Figure 3 is a transverse view taken on the line 3—3 of Figure 2 in the direction of the arrows;

Figure 4 is a transverse view taken substantially in the line 4—4 of Figure 2 and in the direction of the arrows, the hinged side of the tub being in the closed position in this illustration;

Figure 5 is a perspective view of the assembled device showing it in the closed position;

Figure 6 is a sectional view showing detail and construction of the hinge together with a squeegee and taken on the line 6—6 of Figure 1 and in the direction of the arrows;

Figure 7 is an enlarged sectional detail in construction with a locking pin employed in connection with the hinged side of the tub;

Figure 8 is a sectional view showing the hinged detail as taken substantially in the line 8—8 of Figure 2 and in the direction of the arrows;

Figure 9 is a perspective view of the same hinge detail of construction;

Figure 10 is an exploded perspective view of a latch used in connection with the hinge of Figures 8 and 9;

Figure 11 is a fragmentary plan view of a safety bar employed in connection with the invention;

Figure 12 is a perspective view of the support for the tub;

Figure 13 is a sectional view taken substan-

2

tially in the line 13—13 of Figure 1 and in the direction of the arrows showing detail of the connection between the water proof flexible side members, and,

Figure 14 is a sectional view taken substantially in the line 14—14 of Figure 1 and in the direction of the arrows showing a suggested means for facilitating moving the patient board into the tub.

As stated previously, the invention has for its main purpose the alleviation of both trouble and expense involved in treating patients whose motor reaction and agility are impaired when the prescribed treatment involves bathing and/or very light exercise. Accordingly, a general description of the operation and suggested mode of utility of the device is set forth at this time.

The portable bath apparatus is adapted particularly for use of individuals having arthritis or similar afflictions such as polio or its effects or, having any illness requiring baths or meticulous handling. The apparatus has three main purposes. The first is the convenient and safe means of handling and bathing such patient in his own room; the second is an economical and convenient means of hot or cold water treatment which is very often recommended to such patients and the third is the safe means of helping such patients from a prone position in bed to a standing position and of course, from a standing position to a prone position in the same bed or another bed when the patients are to be moved from one place to another. Light exercise is usually recommended for arthritics, which means that patients must be helped from the bed several times a day. This is very difficult, especially for those who care for the many cases involving locked hips, knees and other joints of the body. Such movement is both hazardous and painful to the patient.

The bath apparatus, which is both light and portable, is used in the bedroom or alongside the bed of the patient. Three lengths of hose or conduits are provided; two for water supply (hot and cold) and one for draining the tub. The drain hose is suggested to be hooked over the shower stall, bath tub, toilet in the bathroom or any other suitable drain employed for any water. The water supply is taken from the bathroom or other faucets. These hoses are installed permanently to the risers or removably attached to the faucets by means of conventional couplings. The other ends of the hoses are attached to the mixing faucet which is attached to the tub of the portable apparatus.

The apparatus is placed close to the bed, standing on the rollers which are at one end of the tub of the apparatus. First, the two catches which hold the undercarriage or support to the bottom of the tub are released. The top of the undercarriage or support is then brought to a

horizontal position. The legs are placed in a vertical position. The gates or support members for the support are swung 90° and are secured to the legs by latches provided thereon. Due to the size of the support or undercarriage, it is, preferably of such size to render it positioned with the tub. One end of the support or undercarriage is secured to the bottom of the tub by means of one or more hinges. This makes it possible to erect the undercarriage with all four legs in place on the floor, while the tub itself is still standing on the rollers provided at one end.

Next, the tub is pulled down to a horizontal position, the two catches under the tub being locked to the undercarriage in order to hold the tub firmly in place. The water supply hoses are then attached as previously described. On one side of the bath tub adjacent the bed, the two pins which lock the hinged side of the bath tub to the ends of the said tub are released. The hinged side of the tub is then lowered to the rest horizontally on the bed. A patient board, which may be of marine plywood or other suitable material is provided which is of expeditiously chosen size so as to fit within the tub and so as to support an average, bigger than average and smaller than average patient. It is used to move the patient from the bed into the tub and also for moving the patient from the tub into the bed. This board has an attached cover of sponge rubber, which has a non-porous surface. This eases the pain caused by moving the patient.

On each side of the board there are two pieces of tape which are used as follows; the board is pulled out of the tub and onto the bed as close to the patient as is practically possible. If possible, the patient is rolled on his side with his back toward the tub. With the board as close as possible, the patient is rolled on the board. Tapes are then placed across the tub and the assistant walks around to the other side, picks up the tapes, pulling the board and patient into the bath tub easily over the small rollers which are placed on the bottom of the tub and on the hinged side for this purpose. The board beneath the patient is now secured to the lifting mechanism at the head of the tub. The crank at the top of the lifting mechanism is then turned, raising the head of the board about five inches. With the board on this angle, the patient's face will be above the water line when the tub is filled.

The next step is to close the hinged side and place the locking pins so as to hold it closed. The safety bar which is attached with a bolt to the top edge of the stationary side of the tub is then swung across the opposite side, where there are two catches located on the top edge of the hinged side of the tub. The assistant presses the bar down against the catches, where they are snapped into locked position. The end of the bar has a flattened portion and is turned down approximately one half inch. This turned down part engages over the outside edge of the hinged side of the tub in order to help arrest the pressure of the water against the tub.

As the next step, the cords running through the grommets in the waterproof material which is attached to the end of the hinged side and to the end of the tub, are drawn up and tied at both ends of the tub. The waterproof material which covers the entire hinge connection between the hinged side and the bottom of the tub joins these waterproof ends, forming one continuous waterproof unit.

A short piece of hose is connected to the mixing faucet. This hose is placed alongside the patient with the open end at the foot of the tub. Before the water is turned on, the drain plug is placed. This drain plug is also the overflow which controls the water line.

The tub is now ready to be filled to the water line. When the tub is filled, a showerhead is attached to the short hose. It is used to bathe the patient and to rinse the tub after the bath is completed.

If a long hot water treatment has been prescribed, the hot water is turned on slowly and regulates the temperature. Any excess water is carried down through the overflow drain plug. When the bath is complete, the overflow plug is removed and the water is drained from the tub. The cords are then untied and the pins are removed allowing the hinged side to be lowered on the bed.

The board containing the patient is still on an angle. While the patient is being dried, most of the drops of water will run out the non-porous rubber cover on the top side of the board as well as off the underside. The crank of the lifting mechanism is then turned to allow the board to be lowered flat on the bottom of the tub. The board is then disconnected from the lifting jack or mechanism. The tapes which are fastened to the board are then placed across the bed. The assistant then goes to the opposite side of the bed, pulls the tapes and returns the patient to the bed.

As the board is pulled from the tub, the squeegee which runs the entire length of the tub squeezes the remaining water from the bottom of the board, thus keeping the bed dry.

The board is then lifted from the bed and placed in a suitable location remote from the device. The hinged side of the tub is then closed and the tub is washed out, preferably with the showerhead. The board is then placed in the tub and washed; following which it is tipped on edge and both the board and tub receive final rinsing.

The board is then placed right in the tub. The catches under the tub are released, and lifting springs which form a part of the undercarriage or support, raise the head end of the tub, causing the water to drain to the foot end. After the tub has remained in this position for a short time to drain, both the board and the interior of the tub are dried.

The tub is then stood on end, and the undercarriage is folded flat against the bottom of the tub. Of course, the drain hose is disconnected prior to standing the tub on end, the hose being suitably cared for after disconnection. The faucets which supplied the water to the tub are now closed, the supply hoses disconnected and their ends are placed in the tub or shower in the bathroom. The hoses are then disconnected from the portable bath one at a time, emptied of water as they are coiled, and then placed in the portable bath tube. The tub is then rolled into a corner of the room or some other convenient place for storage.

The same apparatus is used for a means of taking a patient from a bed to a standing position and vice versa. When the device is used in this capacity, the tub is placed beside the bed in the same position as was used in bathing the patient. The hinged side of the bath is open and placed horizontally on the bed. The board

is pulled out of the tub and placed next to the

patient, who is placed on the board and pulled into the tub, as formerly described.

The side of the tub is closed and secured. The safety bar is put in locked position and the assistant steps to the head of the tub. With one hand placed on the top edge of the side of the tub, the assistant releases the catches with the other hand. Lifting with one hand with the help of the spring and placing the other hand in front of the patient, the tub is stood on end. Checking the position of a suitable ramp, the assistant then gives the crutches to the patient, releases the safety bar and assists the patient down the ramp to the floor. In order to return the patient to the bed the same procedure is reversed.

The structure involved in performing these functions is as follows: A support or under-carriage generally indicated at 10 consists of four legs 12, 14, 16, and 18 respectively. A substantially square frame having sides 20, 22, 24 and 30 respectively is secured at the upper ends of the legs thereby forming a table top. Frames or gates 32 and 34 respectively are hinged by means of the collars 38 to the legs 14 and 18 respectively. These gates have means operatively connected therewith for releasably latching them to the respective legs 16 and 12. The latching means is seen best at Figures 8-10. Since both latching devices are identical, a single description suffices for both of them. The structures secured to the gate 32 includes a piece of angle iron 40 with a pin 42 passed therethrough and also through a part of the framing of the gate. This pivot pin has a function of a latchkeeper in that the latch arm 44 is provided with a notch 46 which is to be removably disposed thereon. The head of the pin 42 prevents sliding movement of the latch arm 44 from the pin 42. A sliding latch 48 with notched tongues 50 and 52 respectively extending therefrom is disposed on one flange of the angle iron 40 and is adapted for reciprocating movement. A pair of slots 54 and 56 respectively are provided therein accommodating the screws 58 and 60 which restrict within limits reciprocatory movement of the sliding latch 48.

The leg 16 has an angle iron piece 62 fixed thereto by welding or the like. A latchkeeper 66 which has a pair of spaced openings 68 and 70 in the bight 72 of a curved portion thereof, is fixed to the angle iron piece 62 in parallelism with the sliding keeper 48. Accordingly, when the frame or gate 32 is moved pivotally about the collars 38 as an axis, the cam portions of the tongues 50 and 52 are adapted to slide over the lower edges of the notches 68 and 70 so that the notch tongues are held in place thereby preventing undesired hinge movement of the frame 32.

The latch arm 44 is pivoted by means of a screw 76, rivet or the like, which passes through a bifurcated bracket 78. The bracket 78 is in turn fixed to one of the flanges of the angle iron piece 62 and at the proper elevation so that the latch arm 44 fits over the keeper pin 42.

The legs 12 and 14 are connected together by means of spacing rods, each of which is indicated at 80, while the legs 18 and 16 are connected together by identical bracing rods 80. Accordingly, when both of the frames or gates 32 and 34 are unlatched and folded inwardly, the legs 12 and 14 are free to pivot as a unit, while the legs 16 and 18 are free to pivot as a unit. Corner brackets 84 and 86 respectively are riveted or

otherwise rigidly fixed to corners of the frame 20 immediately above the legs 12 and 14. These legs are pivoted by means of suitable pins to the angle brackets whereby the two legs 12 and 14 are capable of the described pivotal movement. The legs 16 and 18 have the plates 90 and 92 respectively pivoted thereto, while the appropriate end of the frame 20 rests on the top of the legs 16 and 18, whereby the legs 16 and 18 are capable of pivotal movement about the pins which pass through the plates 90 and 92. Accordingly, the tub generally indicated at 100 is fixed rigid with the plates 90 and 92 by means of pivotal bolts or the like which pass through the rails 102 and 104 of the tub. Accordingly, when the tub is in the horizontal position it is adapted to rest on the frame 20. But when the tub is in a vertical position the legs 14 and 12 may be moved as a unit against the bottom of the tub and the legs 16 and 18 may also be moved against the bottom of the tub so as to collapse the under-carriage or support for the purpose set forth previously.

Reference is now made primarily to Figure 1 wherein the tub 100 is illustrated. This tub includes a bottom 106, a side 108, a second side 110, a head or upper end 112 and a lower or foot end 114. The foot end is provided with a number of casters or rollers 116 so that the tub together with its support may be moved from one place to another conveniently.

The side 110 is connected with the bottom 106 by means of one or more piano-type hinges 120. One leaf 122 of the hinge illustrated in Figure 6 is secured to the bottom 106 while the other leaf 124 is secured to the side 110. A water-proof covering 128 is disposed around the hinge and tucked under the leaves thereof so as to provide a water tight connection between the side 110 and the bottom 106.

A longitudinal rib 130 having a head 132 with small ribs 134 thereon is fixed to the side 110 by means of a clamp strap 136 and a number of bolts 138. The function of this resilient member is that of a squeegee for cleaning water of the patient board 140 (Figure 1) as it is moved thereover.

Flexible end members 142 and 144 which are also resilient and water-proof, are secured to the ends 114 and 112 respectively and also to the end edges of the hinged side 110 of the tub. These side pieces form a continuation of the cover 128 (see Figure 13) so as to prevent leakage. A vertical strap 150 is secured to the inner edge of each flexible end piece pressing it firmly to the appropriate end of the tub. Rivets are used in holding the strap 150 in place. These rivets also pass through the bottom framing (see Figure 13) 154 of the end 114 and a similar construction is provided in connection with the end 112.

An identical arrangement including a strap 150 is used for holding the edge of each flexible end piece 142 and 144 to the ends of the hinged side 110 of the tub.

A draw string 160 is passed through successive grommets in the end piece 142 while an identical draw string 162 is passed through grommets successively placed in the end piece 142.

When the hinged side 110 is moved to the vertical position, that is, parallel to the side 108, the draw strings 160 and 162 are pulled so as to hold the flexible end pieces in place (see Figure 4).

After the hinged side 110 is moved to such po-

sition that it is parallel to the side 108, pins 166 are passed through the apertured leaf 170, one of which is secured to each end 112 and 114 of the tub. These pins 166 also pass through sleeves 172 which are welded or otherwise fixed immovably to the upper edge of the hinged side 110. Hence, those ends of the side 110 are held releasably in place with respect to the ends 112 and 114 of the tub. A chain 176 or other equivalent flexible member holds each pin 166 adjacent the appropriate leaf.

However, in order to assure that the water pressure will not buckle the hinged side 110, a safety bar 190 is pivoted to the upper edge of the side 108 and is adapted to swing across the tub so as to be releasably held between the two latches 192 and 194, both of which are of conventional description, being of the slide bolt type. The extreme end of the safety bar 190 has a bent end portion 198 at substantially right angles to the longitudinal axis of the bar 190. This is adapted to overlie a part of the outside edge of side 110 so as to hold it in place, preventing bending of the side member 110 at this point.

The board 140 has a recess 200 at one end so as to provide room for the drain pipe and water line level member 204. At the opposite end of the board 140, there is a substantially triangular member 206 having its apex at the most remote position with respect to the board 140. A pair of straps 208 and 210 respectively are affixed to the undersurface of the board 140 so as to manipulate the board as previously described.

The triangular member 206 is adapted to be removably fastened in the hook 214 which is secured to the collar 216. This collar is disposed on the screw 218 which is threadedly received in a threaded member 220. The threaded member 220 is secured to the end 112 and has a crank or handle 222 at the upper end thereof. This crank is adapted to be rotated whereby the screw is elevated, thereby lifting the hook 214 therewith so as to raise the board 140 or so as to lower the same (see Figure 2).

In order to slide the board 140 over the side 110 while it is substantially parallel to the bottom 106, a number of rollers 230 are secured to the bottom 106 and to the inside surface of the side 110 respectively. These rollers are mounted on pins 232 which are carried by the brackets 234, the brackets in turn being welded or otherwise rigidly secured to the bottom 106 and the hinged side 110. Hence, the board 140 is simply slid directly on the rollers 230.

Since the tub is to be pivoted with the plates 90 and 92 respectively about the appropriate pins as an axis, assistance for the pivotal movement of the tub is provided by way of spring action.

The springs 245 and 246 are secured to the frame 20 and also to the cranks 248 and 250 respectively. Each crank is in turn secured to the bottom structural members 102 and 104. When the tub is in the horizontal position as disclosed in Figure 2, the springs are stretched. But, when the tub is to be lifted so as to pivot, the springs assist in this pivotal movement.

In order to hold the tub in the position as shown in full line in Figure 2, the locking type pivoted supports 260 and 262 respectively are supplied. They are secured respectively to the tub framing members 102 and 104 and to appropriate collars provided on the legs 16 and 18. The locking type supports 260 and 262 are of the common type employed in card tables.

The level maintaining drain pipe 204 is remov-

ably disposed in a suitable opening provided in the bottom 106 of the tub and has conventional coupling facilities at the lower end thereof for connection with the drain hose 270. An appropriate gasket 272 is disposed in the opening in the bottom 106 so as to provide a water tight connection at this point. Removal of the pipe 204 from the coupling 274 which is permanently attached to the bottom 106, allows the water to drain through the hose 270.

A water mixing faucet 276 is secured to the upper edge of the side 108 and has a hose 278 removably fixed at the end thereof. Accordingly, through the utility of this structure appropriate and proper temperature of the liquid entering the tub may be obtained.

As shown in Figure 5, there is a pair of latches 280 and 282 firmly secured to the bottom surface of the bottom 106 of the tub. These latches releasably hold the straps 284 and 286 against the bottom surface of the said bottom 106. Since these straps are fixed to the frame 20, the frame is also held firmly but releasably against the said bottom surface. In collapsing the undercarriage or support, it is held in place in this manner, so that the entire device may be moved from one place to another by simply rolling it on the casters or rollers 116.

Appropriate handles 290 are welded or otherwise rigidly fixed to the outside surface of the side 110. To this expedient the side 110 may be lifted about the hinge pin 120 as an axis. Similar handles 292 are rigidly secured to the undersurface of the bottom 106 so as to maneuver the entire device when it is on casters 116.

From the foregoing a clear understanding of the operation and structure of the invention should be apparent to those skilled in the art. It is appreciated that certain variations may be made without departing from the spirit of the invention.

Having described the invention, what is claimed as new is:

1. A bathing apparatus comprising a portable and collapsible tub stand, a tub hingedly secured to said stand, and one of the side walls of said tub being hinged so that a patient may be moved into the tub through the opening formed in the tub by opening the side of the tub.

2. A bathing apparatus comprising a portable and collapsible tub stand, a tub hingedly secured to said stand, one of the side walls of said tub being hinged so that a patient may be moved into the tub through the opening formed in the tub by opening the side of the tub, and a flexible end piece secured to each end of the hinged side wall and the ends of the tub to seal hinged side when it is in the tub closing position.

3. A bathing apparatus comprising a portable and collapsible tub stand, a tub hingedly secured to said stand, one of the side walls of said tub being hinged so that a patient may be moved into the tub through the opening formed in the tub by opening the side of the tub, a flexible end piece secured to each end of the hinged side wall and the ends of the tub to seal hinged side when it is in the tub closing position, a patient retaining board smaller than the bottom of the tub adapted to support the patient while the patient is in bed, and means carried by the bottom of the tub and the hinged wall for facilitating sliding the board over the hinged wall inside surface and in the tub.

4. A bathing apparatus comprising a portable and collapsible tub stand, a tub hingedly secured

to said stand, one of the side walls of said tub being hinged so that a patient may be moved into the tub through the opening formed in the tub by opening the side of the tub, a flexible end piece secured to each end of the hinged side wall and the ends of the tub to seal hinged side when it is in the tub closing position, a patient retaining board smaller than the bottom of the tub adapted to support the patient while the patient is in bed, means carried by the bottom of the tub and the hinged wall for facilitating sliding the board over the hinged wall inside surface and in the tub, a safety bar for said tub, and a closure carried by the tub holding the bar releasably across the tub.

5. A bathing apparatus comprising a portable and collapsible tub stand, a tub hingedly secured to said stand, one of the side walls of said tub being hinged so that a patient may be moved into the tub through the opening formed in the tub by opening the side of the tub, a flexible end piece secured to each end of the hinged side wall and the ends of the tub to seal hinged side when it is in the tub closing position, a patient retaining board smaller than the bottom of the tub adapted to support the patient while the patient is in bed, means carried by the bottom of the tub and the hinged wall for facilitating sliding the board over the hinged wall inside surface and in the tub, and means carried by the board and one end of said tub for raising said board while in the tub.

6. A bathing apparatus comprising a portable and collapsible tub stand, a tub hingedly secured to said stand, one of the side walls of said hub being hinged so that a patient may be moved into the tub through the opening formed in the tub by opening the side of the tub, a flexible end piece secured to each end of the hinged side wall and the ends of the tub to seal hinged side when it is in the tub closing position, a patient retaining board smaller than the bottom of the tub adapted to support the patient while the patient is in bed, means carried by the bottom of the tub and the hinged wall for facilitating sliding the board over the hinged wall inside surface and in the tub, and said tub having rollers at one end thereof so that when said support is collapsed and the tub set on the rollers it may be easily moved.

7. A bathing apparatus adapted to be used in removing a patient from a bed and for bathing the patient comprising an undercarriage, a tub secured to said undercarriage, said tub having a side hingedly connected to the bottom thereof whereby the side may be opened to a position parallel to the mattress of the bed wherein the patient is located, means for sealing the hinge

connection between the hinged side and the bottom of the tub, and means carried by the tub for mixing water so as to obtain the proper temperature prior to admission of the water in the tub.

5 8. A bathing apparatus adapted to be used in removing a patient from a bed and for bathing the patient comprising an undercarriage, a tub secured to said undercarriage, said tub 10 having a side hingedly connected to the bottom thereof whereby the side may be opened to a position parallel to the mattress of the bed wherein the patient is located, means for sealing the hinge connection between the hinged 15 side and the bottom of the tub, means carried by the tub for mixing water so as to obtain the proper temperature prior to admission of the water in the tub, means for sealing and rendering waterproof the ends of the hinged side, and 20 a drain for maintaining a fluid level in the tub.

9. A bathing apparatus adapted to be used in removing a patient from a bed and for bathing the patient comprising an undercarriage, a tub secured to said undercarriage, said tub 25 having a side hingedly connected to the bottom thereof whereby the side may be opened to a position parallel to the mattress of the bed wherein the patient is located, means for sealing the hinge connection between the hinged 30 side and the bottom of the tub, means carried by the tub for mixing water so as to obtain the proper temperature prior to admission of the water in the tub, and means hingedly connecting the tub with the undercarriage so that the tub 35 may be pivoted for draining the tub and also for moving the patient in the tub to a substantially vertical position.

10. The combination of claim 9 and a patient board, and means disposed on the bottom of 40 said tub and on said hinged side for facilitating rolling the patient board in the tub.

BERNARD E. McLAUGHLIN.
